UNITED STATES PATENT OFFICE.

HENRY G. SCHWARZ, OF DENVER, COLORADO.

BREAKER AND DRIER.

1,217,351.

Specification of Letters Patent. Patented Feb. 27, 1917.

Application filed May 12, 1915. Serial No. 27,549.

To all whom it may concern:

Be it known that I, HENRY G. SCHWARZ, a citizen of the United States, residing at Denver, in the county of Denver and State 5 of Colorado, have invented certain new and useful Improvements in Breakers and Driers, of which the following is a specification.

This invention relates to machines for use 10 in breaking, pulverizing and drying substances, and its primary object resides in providing a machine of simple construction which by rotation, gradually reduces material fed thereinto, to a desired fineness.

Another object of my invention resides 15 in providing in a machine of the character described, means which in coöperation with the breaking elements, cause liquid contained in the material under treatment to be 20 removed by evaporation, and still another object of the invention resides in combining with the means mentioned hereinbefore, a device or devices for pulverizing the material before it is discharged from the 25 machine.

By virtue of its above enumerated properties, my improved machine is particularly adapted for the treatment of substances of a tenacious and plastic character such as 30 clay, kaolin, filter press cakes formed in processes for the production of sugar, and other similar materials and it may also be effectively employed to remove the liquid constituents of semi-liquid substances while 35 the solid parts of the same are broken into granular or pulverous particles of a substantially uniform size.

With the above and other objects in view, all of which will be fully set forth in the following description, my improved breaker 40 consists in its preferred form of the mechanical devices shown in the accompanying drawings in the various views of which like parts are similarly designated, and in which 45 Figure 1 is a side elevation of the machine,

Figs. 2 and 3, conjointly, a longitudinal section through the rotary cylinder in which the material is subjected to the consecutive 50 actions which effect the gradual reduction of its solid matter and the evaporation of its liquid constituents.

Fig. 4, a fragmentary section along the line 4—4, Fig. 2.

Fig. 5, a transverse section along the line 55 5—5, Fig. 2,

Fig. 6, a similar section taken along the line 6—6, Fig. 2,

Fig. 7, a cross section along the line 7—7, 60 Fig. 2,

Fig. 8, a section taken on the plane represented by the line 8—8, Fig. 2,

Fig. 9, a fragmentary section along the line 65 9—9, Fig. 2, drawn to an enlarged scale;

Fig. 10, a transverse section along the line 10—10 Fig. 3,

Fig. 11, a transverse section taken along the line 11—11, Fig. 3, and

Fig. 12, a similar section taken along the 70 line 12—12, Fig. 3.

Referring more specifically to the drawings, my improved breaker and drier consists of a cylindrical drum 2 which through the intermediary of peripheral tread rings 75 3 is rotatably supported upon sets of rollers 4.

The drum is connected at its feed end with a furnace 5 of suitable construction and at its opposite or discharge end with a suitable device for drawing the heated gases from the furnace through the cylinder for the purpose of exsiccatting the material under treatment.

In the construction shown in the drawings, a fan 6 is employed to draw the gases from the furnace, although a stack or other draft-inducing means may be used with equally effective results.

The drum is inclined toward its discharge 90 end, whereby material fed into its opposite end through a conduit 7, is compelled to slowly advance through the cylinder while being subjected to consecutive actions of a series of elements which coöperatively effect a gradual reduction of the solids in the material, to the desired size, and the evaporation of liquids with which said solids were associated.

The rotatably supported drum is driven 100 through the instrumentality of a pinion 8 which meshes with a gear fixed upon the circumferential surface of the cylinder as at 9.

The cylinder is interiorly divided into sections which are differentiated by the character of the different elements which by their actions upon material fed into the cylinder through the conduit 7, gradually reduces its 105

solids to the required size while exposing its liquid constituents to the evaporative influence of the heated gases which are drawn from the furnace through the cylinder by means of the exhaust fan 6.

5 The arrangement of the coöperative elements assembled in the drum, is varied in accordance with the character of the material to be treated, as will hereinafter be 10 more fully explained, that shown in the drawings being particularly designed for the treatment of the mixture of filter-press cakes and waste water obtained in the molasses desugaring process of a beet sugar factory.

15 Commencing at its feed end the cylinder is divided into—

1st—an exsiccation section A in which the greater portion of the liquid contents of the 20 material is evaporated by retarding its progress through the inclined drum and thereby fully exposing it to the influence of the hot gases which are constantly drawn from the furnace by the action of the fan.

25 2nd—a reduction section B in which the material is subjected to a series of consecutive breaking actions which gradually reduce the size of its particles while exposing them to the influence of the gases for the 30 evaporation of the liberated moisture.

30 3rd—a drying section C in which the greater part of the moisture still remaining in the reduced material is removed.

4th—a final reduction section D in which 35 the material is broken to a fineness suitable for pulverization.

5th—a pulverizing mill E in which the material is ground to a powder, and

40 6th—a final drying section F in which 40 the greater part of the moisture contained in the pulverous matter is removed.

In treating in a machine of the construction above outlined, the residuant matter of the desugaring process hereinbefore referred to, which includes from 45 to 60% liquid, a pulverous product is obtained containing less than 10% moisture.

The first mentioned section A, at the feed end of the drum contains a series of successively disposed elements 14 which operate to retard the movement of the material and thereby thoroughly expose its parts to the evaporative influence of the heated gases before it enters the next section B.

55 The elements 14 of the exsiccation section are with the above objects in view, each composed of a series of flights 10 which project radially inwardly from the interior surface of the cylinder.

60 At the points at which the flights of each series are attached to the cylinder, a circular riffle 12 composed of an inwardly projecting ring is disposed to retard the inward flow of the liquid or semi-liquid material, 65 and secured to this ring between the flights

of each series are buckets 13 which serve to carry the material upwardly during rotation of the cylinder.

The flights of the first element are as illustrated in Fig. 4, secured at their inner ends 70 to a concentric ring 15 to withstand the impact of the material as it is fed into the cylinder through the conduit 7, while the corresponding flights of the other elements are loose as shown in Fig. 5.

75 Four of the flights of each element 14, which are positioned at quadrant points of the cylinder and designated by the numeral 16 in Figs. 5 and 6, are extended to a point of intersection in the axis of the same at 80 which point they are secured together by rivets or other suitable means.

85 The flights of the various elements are with the exception of those of the first element, slanted laterally with relation to the axis of the cylinder to still further retard the inward movement of the material, and commencing with the second element the flights of the succeeding elements are progressively reduced in width.

90 The inward flow of the semi-liquid material fed into the cylinder through the conduit 7, is retarded by the riffles 12 while the buckets 13 by rotation of the cylinder, lift the material to a point at which it is discharged onto the subjacent flights.

95 While sliding along the flights toward the center of the drum, the material is fully exposed to the influence of the gases which are drawn through the cylinder by the 100 action of the fan, and the material thus advances from one element to the other in each of which the above treatment is repeated, until it enters the reduction section B in a comparatively dry condition.

105 The second section of the cylinder contains a series of successively arranged elements which act upon the material to gradually reduce the size of its particles and which at the same time retard its progress sufficiently to cause the moisture liberated during the breaking actions to be evaporated by contact with the heated gases.

115 The first element 17 of the series contained in the reduction section, consists of a plate 18 extending diametrically across the cylinder and provided at each side with a retaining rim 19 and a number of angular 120 cutters 20. The material entering the section is lifted by the plate 18 until in the rotation of the drum the plate approaches the vertical, when the material by its own gravity slides downwardly and by contact with the cutters 20 is broken into smaller 125 particles.

130 While sliding along the plate the material is again exposed to the influence of the heated gases for the evaporation of its liquid constituents part of which are liberated by breaking the material into smaller parts

5 The particles passing between the cutters on the plate 18 advance onto the next element which comprises a series of inclined riffles 21 slantingly secured upon the interior surface of the drum. These riffles lift the material by rotation of the drum and cause it to fall through the current of heated gases passing constantly through the cylinder, thereby continuing the breaking and 10 evaporating processes.

10 The slanting position of the riffles impels the material toward the next element 22 of the series which consists of an annular inwardly projecting ring 23 provided with a series of equidistant slots 24, as best shown in Fig. 7, and at the edges of said slots with slantingly disposed baffle- and cutter-blades 25 shown in detail in Fig. 9.

20 The ring 23 has at its inner edge, cylindrical and flaring flanges 26 and 27 which extend in a direction opposite to that in which the material travels through the drum and which serve in the operation as an auxiliary breaking medium and as a deflective 25 agent for compelling the material to pass through the openings 24.

25 While advancing toward and through the openings of the ring 23 the material is by contact with the cutter blades 25 broken into still smaller particles which by the next element of the section which comprises a number of spiral shovels 28, are lifted to the upper portion of the drum and at the same time advanced toward the last element 29 35 of the section.

30 After being lifted by the spiral blades the material falls again through the current of the heated gases before it engages the next element of the series, and the lumps 40 contained in the material are thereby still further broken while all the moisture liberated in the breaking process is evaporated.

35 The last element 29 of the series contained in section B of the machine, consists of a 45 funnel-shaped conduit composed of convergently disposed, equidistantly spaced bars 30 which are separated from the surface of the drum.

40 The bars have at their inner edges a number 50 of inwardly pointing teeth and they are connected at their forward ends by a flange 31 provided with slots 32 formed between divisional parts 33 which likewise are provided with inwardly pointing teeth.

55 The material as it passes and repasses through the spaces between the bars and the slots in the flange and is brought in contact with the teeth, is broken into small particles of substantially uniform size which 60 upon entering the next section C of the machine are subjected to a drying action for the purpose of further removing their liquid constituents before they are finally reduced in section D to a size suitable for 65 pulverization in section E.

Section C comprises to this end a series of flues 34 which are formed by longitudinally extending plates 35 arranged cross-sectionally in reticulate order.

70 The ends of the plates at the entrance of the section are placed out of alignment to provide riffles which lift the material and compel it to enter the flues. While passing through the flues by the inclination of the rotary drum, the material is brought into 75 intimate contact with the heated gases which are drawn through the flues by the operation of the fan, with the result that when the granular mass is discharged from the flues into the final breaking section D, it is 80 in a comparatively dry condition.

85 Section D contains a single breaking element 36 which consists of an open-ended conduit 37 which is spaced from the wall of the cylinder and which at its outer end has an inwardly extending circular flange 38.

90 The conduit and its flange are both provided with a multitude of inwardly pointing prongs which are formed by punching the metal of which the parts are composed and bending the punched-out portions inwardly.

95 By this method the conduit and its flange are at the same time provided adjacent its prongs with foraminations 39 through which the material passes into the space between the conduit and the surface of the cylinder and into the grinding section E.

100 The material passing through the element 36 is by contact with the prongs reduced to grains of practically uniform size the maximum mesh of which is determined by the size of foraminations, and in this condition the material enters the grinding section in which it is reduced to a powder.

105 The grinding section E and the following section F of the drum are made of larger diameter than the preceding part of the same, partially for the purpose of providing a runway for the balls or pebbles of the mill, but more especially with the object of reducing the velocity of the gases at the discharge end of the machine and of thereby preventing the loss of dust which otherwise would be carried away by suction.

110 The pulverizing section E of the machine 115 contains an annular runway 40 determined at one end by the offset formed by the enlargement of the drum at the end of the preceding section and at its opposite end by a perforated annular plate 41.

115 The runway is provided with a mass of pebbles or balls 42 like those used in the ordinary tube mill, to reduce the material to a powder which passes through the perforations of the plate 41 into the last section F 125 of the machine which merely contains two plates 43 placed diametrically with relation to the drum at right angles to each other, as shown in Fig. 12.

120 The pulverous matter sliding along the 130

plates is once more exposed to the influence of the gases for the purpose of subjecting the material to a final drying action.

Having thus described the construction and operation of the machine as it is shown in the drawings, I desire to call attention to different modifications which may be resorted to for the purpose of adapting the machine for the treatment of materials of different character.

10 Aside from the obvious modifications in the number of breaking elements and their respective constructions to adapt the machine for reducing materials of different degrees of tenacity, hardness and compactness, the sections for drying the material by evaporation of its liquid constituents may be reduced in number, modified in construction, or in case the machine is designed for 15 the treatment of dry materials, entirely eliminated.

In the last mentioned instance, both the furnace and the fan may be dispensed with and the machine is operated solely for the 20 automatic granulation or pulverization of materials of the class for the treatment of which the machine is particularly adapted.

It will furthermore be understood that in case it is desired to obtain a granular product, the pulverizing section is omitted, or that in case a product of more than ordinary fineness is required, two or more pulverizing mills may be arranged at the discharge end of the machine in successive order.

25 35 Having thus described my invention what I claim and desire to secure by Letters-Patent is:

1. In apparatus of the character described, a rotary drum, means for subjecting 40 material passing therethrough to the exsiccative influence of heat, and means for feeding material into an end of said drum, the said drum having interiorly, elements which during rotation of the drum, disintegrate material passing through the same, and elements which expose the material to the influence of the heat, the said elements being successively arranged to include commencing at the feed end of the drum, an 45 exsiccation element, a series of breaking elements which progressively disintegrate the material, a second exsiccation element, a final breaking element, a pulverizing element, and a final exsiccation element.

50 55 60 65 2. In apparatus of the character described, a rotary drum, means for subjecting material passing therethrough to the exsiccative influence of heat, and means for feeding material into an end of said drum, the said drum having interiorly, elements which during rotation of the drum, disintegrate material passing through the same, and elements which expose the material to the influence of the heat, the said elements being successively arranged to include commenc-

ing at the feed end of the drum, an exsiccation element, a breaking element, a second exsiccation element, a final breaking element, a pulverizing element and a final exsiccation element.

3. In apparatus of the character described, a rotary drum, means for subjecting material passing therethrough to the exsiccative influence of heat, and means for feeding material into an end of said drum, the 70 said drum having interiorly, elements which during rotation of the drum, disintegrate material passing through the same, and elements which expose the material to the influence of the heat, the said elements being successively arranged to include commencing at the feed end of the drum, an exsiccation element, a breaking element, a second exsiccation element and a final breaking element.

4. In apparatus of the character described, a rotary drum, means for subjecting material passing therethrough to the exsiccative influence of heat, and means for feeding material into an end of said drum, the 75 said drum having interiorly, elements which during rotation of the drum, disintegrate material passing through the same, and elements which expose the material to the influence of the heat, the said elements being successively arranged to include commencing at the feed end of the drum, a breaking element, an exsiccation element and a final breaking element.

5. In apparatus of the character described, a rotary drum, means for subjecting material passing therethrough to the exsiccative influence of heat, and means for feeding material into an end of said drum, the 80 said drum having interiorly, elements which during rotation of the drum, disintegrate material passing through the same, and elements which expose the material to the influence of the heat, the said elements being successively arranged to include commencing at the feed end of the drum, an exsiccation element, a breaking element, a second exsiccation element and a final breaking element.

6. In apparatus of the character described, a rotary drum, means for subjecting material passing therethrough to the exsiccative influence of heat, and means for feeding material into an end of said drum, the 85 said drum having interiorly, elements which during rotation of the drum disintegrate material passing through the same, and elements which expose the material to the influence of the heat, the said elements being successively arranged to include commencing at the feed end of the drum, a breaking element, an exsiccation element, a final breaking element, and a pulverizing element.

7. In apparatus of the character described, a rotary drum, means for subjecting ma-

- terial passing therethrough to the exsiccative influence of heat, and means for feeding material into an end of said drum, the said drum having interiorly elements which during rotation of the drum, disintegrate material passing through the same, and elements which expose the material to the influence of the heat, the said elements being successively arranged to include commencing at the feed end of the drum, an exsiccation element, a series of breaking elements which progressively disintegrate the material, a second exsiccation element, and a final breaking element.
15. 8. In apparatus of the character described, a rotary drum, means for subjecting material passing therethrough to the exsiccative influence of heat, and means for feeding material into an end of said drum, the said drum having interiorly, elements which during rotation of the drum, disintegrate material passing through the same, and elements which expose the material to the influence of the heat, the said elements being successively arranged to include commencing at the feed end of the drum, an exsiccation element, a series of breaking elements which progressively disintegrate the material, a second exsiccation element, and a final breaking element.
20. 9. In apparatus of the character described, a rotary drum, means for subjecting material passing therethrough to the exsiccative influence of heat, and means for feeding material into an end of said drum, the said drum having interiorly, elements which during rotation of the drum, disintegrate material passing through the same, and elements which expose the material to the influence of the heat, the said elements being successively arranged to include commencing at the feed end of the drum, an exsiccation element, a series of breaking elements which progressively disintegrate the material, a second exsiccation element, a final breaking element, and a pulverizing element.
25. 10. In apparatus of the character described, a rotary drum, means for subjecting material passing therethrough to the exsiccative influence of heat, and means for feeding material into an end of said drum, the said drum having interiorly, elements which during rotation of the drum, disintegrate material passing through the same, and elements which expose the material to the influence of the heat, the said elements being successively arranged to include commencing at the feed end of the drum, a series of breaking elements which progressively disintegrate the material, an exsiccation element, and a final breaking element.
30. 11. In apparatus of the character described, a rotary drum, means for subjecting material passing therethrough to the exsiccative influence of heat, and means for feeding material into an end of said drum, the said drum having interiorly, elements which during rotation of the drum, disintegrate material passing through the same, and elements which expose the material to the influence of the heat, the said elements being successively arranged to include commencing at the feed end of the drum, a series of breaking elements which progressively disintegrate the material, an exsiccation element, a final breaking element, and a pulverizing element.
35. 12. In apparatus of the character described, a rotary drum having interiorly, an inwardly extending ring provided with openings for the passage of material passing lengthwise through the drum, and in advance of said openings, cutting-members which disintegrate the material.
40. 13. In apparatus of the character described, a rotary drum having interiorly, an open-ended conduit spaced from the interior surface of the drum and having in its circumferential surface, openings for the discharge of material into the said space, and inwardly projecting teeth which disintegrate the material passing through the conduit.
45. 14. In apparatus of the character described, a rotary drum having interiorly, an open-ended conduit spaced from the interior surface of the drum and having an inwardly extending flange at one of its ends, the said conduit and the said flange having openings for the discharge of material into the said space, and inwardly projecting teeth which disintegrate the material passing lengthwise through the drum.
50. 15. In apparatus of the character described, a rotary conduit, and means for subjecting the contents thereof to the exsiccative influence of heat, the said conduit having interiorly, elements adapted for action by its rotation, to break material passing through the conduit into smaller particles, and an element adapted to expose the material to the influence of the heat, comprising a retaining riffle extending inwardly from the interior surface of the drum, a series of flights extending radially inwardly from the said riffle, and buckets adjacent said riffle for lifting the material from the bottom portion of the drum and discharging it onto the said flights.
55. 16. In apparatus of the character described, a rotary drum, a circular retaining riffle projecting inwardly from the interior surface thereof, and plates extending from the said surface adjacent the riffle, radially inwardly and having surfaces disposed to guide material lifted by rotation of the drum, transversely of the drum toward the axis of the same.
60. 17. In apparatus of the character described, a rotary drum, circular retaining riffles projecting inwardly from the interior surface thereof, buckets between said riffles for lifting material by rotation of the drum, and plates extending radially inwardly from the said surface, and having surfaces disposed to guide material dis-
65. 18. In apparatus of the character described, a rotary drum having interiorly, elements for breaking by rotation of the drum, material passing through the same

charged from said buckets, toward the axis of the drum.

18. In apparatus of the character described, an axially inclined rotary drum, 5 circular retaining riffles extending inwardly from the interior surface thereof, laterally slanting buckets between the riffles, and plates extending longitudinally from the interior surface of the drum, radially inwardly, for guiding material lifted by rotation of the drum, toward the axis of the same, and slanting laterally with relation to said axis.

19. In apparatus of the character described, 15 a rotary conduit and a reticularly arranged series of plates therein to provide

a series of longitudinal flues for the purpose specified.

20. In apparatus of the character described, a rotary drum, and a pair of plates 20 extending longitudinally of the drum in engagement with its interior circumferential surface and across each other axially of the drum, to guide material lifted by rotation of the drum toward their point of intersection.

In testimony whereof I have affixed my signature in presence of two witnesses.

HENRY G. SCHWARZ.
